UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR CONSTRUCTION.

1,244,808.

Specification of Letters Patent. Patented Oct. 30, 1917.

Application filed August 2, 1916. Serial No. 112,708.

To all whom it may concern:

Be it known that I, JACOB H. WEISBROD, residing at St. Louis, Missouri, and being a citizen of the United States, have invented 5 certain new and useful Improvements in Car Constructions, of which the following is a full, clear, and exact description, such as will enable others skilled in the art to which it appertains to make and to use the 10 same, reference being had to the accompanying drawings, which illustrate the preferred form of the invention, though it is to be understood that the invention is not limited to the exact details of construction 15 shown and described, as it is obvious that various modifications thereof within the scope of the claims will occur to persons skilled in the art.

In said drawings:

20 Figure 1 is an elevation of half of a box car equipped with one form of the device;

Fig. 2 is a right and left vertical section taken on lines A—A and B—B, respectively, of Fig. 1;

25 Figs. 3 to 6 inclusive show modified forms of sills having means for supporting and uniting the floor and wall members;

Fig. 7 illustrates the form shown in Figs. 1 and 2 upon a larger scale; and

30 Fig. 8 is a section through the side door threshold, as for example on line B—B, showing the elevated plate of the sill cut away to allow the floor boards to be extended beyond the web, and a sill reinforcing angle supporting the extending floor boards within the zone of the door.

An object of the invention is to provide a 35 box car with a reinforced metal side sill, having a web portion formed in part from a plurality of thicknesses of metal with laterally extending top and bottom flanges adapted to stiffen said web, with said flanges so disposed that one of them can be utilized as a floor support, all combined with a side 45 sheathing lapping the floor and sill web to form a grain-tight joint where the portion of such box car joins the sill. An outer framing of metal is also employed in such manner as to strengthen the car body structure and to hold the bottom board of the side sheathing in proper relation to the sill and flooring.

The floor and wall joint for single 50 sheathed cars includes a side sill made up of a plurality of members collectively op-

erating to produce a grain-tight joint at wall and floor and to support and unite the same.

One of the advantages of the construction is that gusset plates at the side sill are unnecessary and variations in the strength of the side sill member as a whole may be brought about by changing the depth of that portion of the sill providing the web extension. This extension is utilized for the purpose of securing the framing posts and 60 braces to the side sill at points above the upper flange of the side sill and to keep the side wall boards between the posts from bulging outwardly.

The arrangement insures at all times a 70 joint which is proof against leakage and which can readily be formed from commercially rolled sections and plates readily obtainable in the open market, and requires no specially rolled or specially shaped member to provide the bond between the floor and wall or sheathing of the car.

Referring specifically to the parts, C indicates generally the side sill which, as shown in Fig. 3, is a built-up structure comprising a bottom angle 9, having a bottom horizontal flange and a vertical web portion 10, and an angle 11, having a horizontal flange 12, being secured to and extending upwardly from said angle 9. Parallel 80 to the web 10 of the angle 9 and the vertical web of the angle 11, is a web plate 13 which is secured in position by a double row of rivets 14, which rivets connect said web plate 13 with the bottom angle 9 and top 85 angle 11, said web plate 13 extending for some considerable distance above the laterally extending upper flange 12 of said angle 11 and, considering the depending leg of the angle 11 and the vertical leg 10 of the angle 9 as webs, it will be noted that there 90 are three vertical web plates in this type of construction.

Resting upon the horizontal inwardly disposed flange 12 of the angle 11 are floor 100 boards 15 which are secured in position by through bolts 16 extending through said wood floor 15 and the inwardly disposed flange 12 of the angle 11. Obviously, before the members of the sill construction 105 are rigidly connected together, angle 11 can be adjusted vertically of angle 9 to raise or lower its flange 12. The floor level can therefore be raised or lowered, or any of different thicknesses of flooring may be used 110

and a predetermined floor level be maintained.

Lapping said floor, the web plate 13, the vertical leg of the angle 11, and the vertical leg of the angle 9, are vertical framing posts 17, which, with the diagonal braces 18, are rigidly secured to said web plate 13, the posts 17 extending farther downwardly and being connected by said double row of 10 rivets 14 to the lapped vertical webs of the side sill.

Secured to the posts and braces 17 and 18 is a wood sheathing 20 comprising a plurality of superposed narrow sheathing 15 planks or boards preferably bolted to said posts and diagonal braces. The bottom board 20^a of said side sheathing is cut away, as shown at 21 in Figs. 3 to 7 inclusive, to clear the portion of the sill web 20 which extends above the upper flange of said sill, said sheathing board 20^a terminating in a thinner lower portion 22 which is interposed between the floor boards 15 and the upwardly extending portion of the web 25 plate 13, so as to close the gap between said web plate 13 and the floor boards, thereby forming a grain-tight joint.

The general type of construction employing a sill built up of commercially rolled 30 sections and plates is followed throughout the several modifications, with the exception of the modification disclosed in Fig. 4, in which latter figure there is employed an angle 9^a with a relatively wide vertical 35 flange 10^a which is lapped by the vertical flange of an angle 11^a having a horizontal flange 12^a on which rests the floor 15, and it is to be noted that the flange, or vertical web, 10^a of the angle 9^a extends above said 40 flange 12^a and laps the lower sheathing board 20^a in Fig. 4, as does the vertical web plate 13 of Fig. 3.

However, like the specific construction disclosed in Fig. 3, the lower sheathing board 45 is attenuated at its lower edge and is disposed between the floor 15 and posts 17.

In Fig. 5, appears another modification in which the sill web is formed by a vertical web portion 25 of a rolled Z-section 26, 50 having top and bottom flanges, while a web plate 13^a is secured to the vertical web 25 of said Z-section, and, as in Figs. 3 and 4, said web plate extends above the top flange 27 of said Z-section 26, the web plate 13^a 55 and the web 25 of the Z-section being secured together by rivets 14, as in Fig. 3.

In Fig. 6, as in the preceding figures, the side sill is a composite structure, but it employs a rolled channel section 30 having 60 inwardly disposed top and bottom flanges, 31 and 32 respectively, and a vertical web 33. Parallelizing the web 33, secured thereto as in Figs. 3 and 5, and extending above the flange 31, is a web plate 13^b.

65 In Fig. 7 the form incorporated in Figs.

1 and 2 is shown on an enlarged scale, and in which a pressed metal angle 35, having a bottom flange 36 and a vertical web 37 extending above the inwardly disposed flange 38 of the top angle 39, is employed.

70 It is to be noted that, in all of the modifications disclosed, the rivets connecting the paralleling portions of the vertical webs of the sill also serve as connecting means for the vertical posts 17 to said sills. For example, in Figs. 3 to 6 inclusive there are shown three rivets extending through the flange 17^a of the post 17, and through one or more thicknesses of the vertical sill web, thereby utilizing the same rivets to connect the several members of the sill and said vertical posts 17, in addition to which in said figures rivets 14^a extend through said flange 17^a the vertical post and through the upward extensions C' of said side sill webs, 80 and it is to accommodate these upward extensions of the sill webs, and in some instances the rivets that connect the extensions with the post flanges, that the lower outer portions of the bottom sheathing 90 boards are gained out or cut away, as shown.

Intermediate the door opening of the car body and the ends of the car, short floor boards may be and preferably are, employed, which floor boards extend across the car 95 from the inner faces of the side sheathing at one side of the car to the inner faces of the side sheathing at the opposite side of the car.

At the door openings it is essential that the floor boards extend outwardly beyond the normal outer line of said boards and as the vertical extensions C' of the sills would otherwise interfere, said vertical extensions C' are preferably cut away at the door openings.

100 Extending substantially throughout the length of the door openings, are angles 40 having vertical web portions 41 riveted to the vertical webs of the side sills and horizontal flange portions 42 extending outwardly therebeyond to serve as supports for the outer portions 15^b of the floor boards 15.

110 The vertical legs or web portions 41 of angles 40 which parallel the vertical web portions of the side sills, are each secured to those portions of one of the side sills by rivets 44 within the zone of the door opening, thereby reinforcing the sill within such zone.

120 Throughout the various forms the upper surface of the top flange of the sill forms a continuous plane surface free from obstructions, whereby the bottom sheathing board may slide thereon during the construction of the car in being positioned against framing 125 posts 17. This and the absence of a direct anchoring engagement between the sill top flange and the bottom of the sheathing is advantageous, as any thickness of sheathing may be used, and the floor boards be caused 130

to crowd the sheathing against the side sill web portion that extends above the top sill flange, and also against the car side framing.

What I claim is:

- 5 1. In combination a side sill comprising joined separately formed members adapted to support and unite a floor and side sheathing and having a seating surface for both forming a continuous plane, said sill including upper and lower flanges, with a web portion extending to a higher plane than said upper flange.
- 10 2. Connected members forming a reinforced side sill construction comprising horizontal flanges and a web portion extending to a plane above said flanges, in combination with a floor and side sheathing resting on one of said flanges and held in interlocked relation with said floor by said web portion, the last mentioned flange being adjustable vertically of said web portion before said members are connected.
- 15 3. In combination, a car sill comprising a plural-part web portion having a bottom flange, one web part having an inwardly disposed flange adapted to be selectively positioned intermediate the top and bottom of said web and secured to an adjacent web part, a floor resting on the latter flange and
- 20 30 a side sheathing extending between said floor and said sill web.
- 25 4. In combination in a railway car, a sill comprising spaced upper and lower flanges, a web portion joined to said flanges and including a web member separately formed

from and extending for some distance above and below said upper flange, a floor resting on said upper flange and a side sheathing held in a space between said floor and the upper part of said web portion.

5. In a railway box car, a grain tight joint comprising an outer frame, a sheathing within and secured in position by said frame, a multipart side sill and a floor lapped by said frame and said sheathing, the sheathing and said floor being supported on a surface of said sill that lies in a single plane.

6. In a railway box car, a side sill extending substantially from end to end thereof, said sill comprising horizontal flanges and a web portion which is formed from a plurality of thicknesses of metal connected with and extending vertically above said flanges, a floor resting on one of said flanges, a side frame, and a sheathing secured thereto.

7. In a railway box car, a side sill extending substantially from end to end thereof, said sill comprising horizontal flanges and a web portion which is formed from a plurality of thicknesses of metal connected with and extending vertically above said flanges, a floor and a sheathing resting on one of said flanges and a side frame on the outer side of said sill secured to said sheathing.

In witness whereof I have hereunto set my hand in the presence of two witnesses.

JACOB H. WEISBROD.

Witnesses:

OSCAR HOCHBERG,
BLASDEL SHAPLEIGH.
